(57) CLAIM

The ornamental design for luminescent portions of a shoe, as shown and described.

DESCRIPTION

FIG. 1 is a top perspective view of luminescent portions of a shoe showing my new design;
FIG. 2 is a front view thereof;
FIG. 3 is a rear view thereof;
FIG. 4 is a right side view thereof;
FIG. 5 is a left side view thereof; and,
FIG. 6 is a top view thereof.
In the drawings, the broken lines in FIGS. 1-6 depict portions of the design that form no part of the claim.
